(57) **CLAIM**

The ornamental design for a truck floor cup holder device, as shown and described.

DESCRIPTION

FIG. 1 is an isometric view of a truck floor cup holder device showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof;

FIG. 7 is a rear elevational view thereof; and,

FIG. 8 is an isometric operational view showing my design. The broken lines showing the portions of the truck vehicle and cups are provided for the purposes of illustrating environmental structure and form no part of the claimed design.
